ATTORNEY.
David E. Lain,

UNITED STATES PATENT OFFICE

CLARENCE D. BALDWIN, OF BELLINGHAM, WASHINGTON

RAILROAD-GAUGE BRIDLE

Application filed July 14, 1928. Serial No. 292,756.

My invention relates to improvements in railroad-gauge bridles and has for an object to provide a rail-road gauge bridle which will be effective in maintaining the railroad-gauge and yet may be quickly installed and removed.

Another object of my improvement is to provide a railroad-gauge bridle which is adjustable without removing the rail fastenings to the bridle.

Another object of my improvement is to provide a simple railroad-gauge bridle which may be installed, removed or adjusted by unskilled operatives.

15 A further object of my improvement is to provide adjustable railroad-gauge retaining means of simple design, not likely to become disorganized and of reasonable cost of construction.

20 Other objects of my improvement will appear as the description proceeds.

I attain these and other objects of my improvement with the mechanism illustrated in the accompanying sheet of drawings in which 25 Figure 1 is a segregated portion of a railroad track with one of my gauge bridles in place thereon, Fig. 2 is an elevation of Fig. 1 in section on line 2—2, Fig. 3 is an end elevation of the retaining sleeve, Fig. 4 is an end elevation of the clamping sleeve and Fig. 5 is an end elevation of the eye clamp.

Similar characters refer to similar parts throughout.

With more particular reference to the designated parts:

Two similar bars 8 and 9 are each provided with a hook 10 on one end and a toothed rack 11 on one side at the other end thereof. Bars 8 and 9 are disposed across the track with 40 their hook ends beneath the rails and engaged with the outer edges of the rail flanges and with their inner ends overlapping in the middle of the track and the racks 11 engaged. There are three rails shown, track rails 6, 6 and guard rail 7. Bar hooks 10, 10 are engaged with the outer edges of the flanges of rails 6, 6. The inner end of bar 8 is downward and its rack 11 is on the upper side thereof, while the inner end of bar 9 is upward and has its rack 11 on the under side

thereof. The said racks 11 lie flatwise together in engagement over their entire contact area.

The two clamping sleeves 15 are alike. One is used to hold the bar 9 against the left-hand rail 6 and said rail in close engagement with hook 10 on bar 9. These clamping sleeves consist of a rectangular sleeve with opening b^{15} therethrough and upwardly inclined lug a^{15} protruding from one end of the upper wall. One of these clamping sleeves has bar 9 extended through its opening b^{15} with lug a^{15} overlying the inner edge of the flange of rail 6 at the left. Opening 12 through bar 9 is disposed adjacent the inner end of clamping sleeve 15 and key 16 is extended therethrough to bear against the said inner end of the sleeve. Preferably the inner edge of key 16 is tapering as is also the inner side wall of opening 12 and key 16 forces hook 10 and lug a^{15} in close engagement with the flange of said rail. Key 16 is preferably provided with tail 17 and an opening through its lower end which protrudes below the bar through which cotter pin 18 is extended to retain the pin in the bar. Eye clamp 19 has head a^{19} with beveled bottom and opening 20 through which is extended bar 8 when said head is caused to bear on the adjacent edge of the flange of rail 6 and said opening is below the bottoms of said rail flanges. Bar 8 is then extended through opening b^{15} in the other sleeve clamp which is placed next the inner edge of the flange of guard rail 7 with inclined lug a^{15} bearing on the top side of said flange. Opening 13 through bar 8 is disposed adjacent the inner end of clamp sleeve 15 when the outer end thereof bears against the flange of rail 7 and the other key 16 is extended through said opening to force said sleeve 15 against the flange of rail 7, the outer edge of the flange of right hand rail 6 in close engagement with the hook 10 on bar 8 and the opposite edges of the flanges of rails 6 and 7 against the beveled under side of head a^{19} of the eye clamp. To promote this clamping effect the inner edge wall of hole 13 is tapered to correspond with the taper of key 16 therein. This key 16 is also provided with a tail 17 and has an opening through its lower end

85 90 95 100

which protrudes beneath the bar and has a cotted pin 18 extended therethrough.

It not infrequently happens that my bridle will be used across a portion of the track

5 where no guard rail is employed. In that case the sleeve 15 on bar 8 is set against the inner edge of the flange of right-hand rail 6 and the key is extended through hole 12 through bar 8.

10 Sleeve 21 is rectangular with either the bottom or top wall extended at one end and has an opening 25 through said extended end 22. Rib 23 is provided across the inside wall at the end opposite 22.

15 Bar 9 is extended through sleeve 21 entering the end having rib 23 therein and, when the racks 11, 11 are engaged, sleeve 21 is passed over the overlapping inner ends of bars 8 and 9 to retain said toothed racks in 20 engagement. Opening 25 in end 22 of the sleeve is made to register with hole 14 through bar 8 and the sleeve 21 is secured in place by extending pin 26 through said holes 14 and 25. Pin 26 preferably has tail 27 on its upper end and a hole through its lower end which protrudes beneath the sleeve and through which is extended cotted pin 28.

Rib 23 is placed to bear against the end of bar 8 when holes 25 and 14 register. Sleeve

30 21 may also be used when inverted and turned end for end. In this case rib 23 would bear against the end of bar 9 and hole 25 in the sleeve would register with a similarly placed hole 14 in bar 9 and pin 26 would be extended 35 through the sleeve wall and through bar 9.

To adjust the gauge of rails 6; 6 sleeve 21 is released from engagement by pin 26 and moved in either direction on the bars till they may be separated and reengaged by racks 40 11, 11 in the desired new setting when sleeve 21 may be returned to its operative position to retain said bar ends in engagement.

Bars 8 and 9 may be disengaged from the rails when their inner ends are free by re- 45 moving keys 16, 16, and moving clamping sleeves 15, 15 and eye clamp 19 out of engagement with the flanges of said rails.

Bars 8 and 9 are made strong enough to resist the thrusts of operation as well as the 50 tension strains thereof.

Having thus disclosed my invention, what I claim as new therein and desire to secure by Letters Patent is,—

1. In a rail-road gauge bridle, two bars with 55 overlapping ends disposed across the track beneath the rails thereof, a hook on each of the outer ends of said bars engaged with the outer edge of the flange of one of said rails, a sleeve clamp reciprocal on each of said bars adjacent the inner edge of the flange of one of said rails, a lug on the outer end of each of said sleeve clamps to bear on the top of said inner edge of one of said rail flanges, a key extended through each of said 60 bars adjacent the inner end of the clamp

sleeve thereon to bear against the same, and means to retain said overlapping bar ends in positive engagement in adjustable positions.

2. In a rail-road gauge bridle, two bars with overlapping ends disposed across the track beneath two track rails and a guard rail adjacent one of said track rails, a hook on the outer end of each of said bars engaged with the outer edge of the flange of each of 70 said track rails, an eye clamp between said guard rail and said track rail adjacent thereto with its head bearing on the adjacent flange edges thereof and its body therebetween with its eye projecting beneath and having one of 75 said bars extended therethrough, a clamp sleeve reciprocally engaged on said one bar with its outer end bearing on the inner edge of the flange of said guard rail, a lug on the outer end of said sleeve clamp bearing on top 80 of said guard-rail flange, a key extended through a hole in said one bar adjacent the inner end of said sleeve clamp to bear thereagainst, another sleeve clamp reciprocal on said other bar with its outer end adjacent the 85 inner edge of the flange of said other track rail, a lug on the outer end of said other sleeve clamp to bear on top of said other track rail flange, a key extended through a hole in said other bar to bear against the inner 90 end of said other sleeve clamp, said overlapping ends of said bars having engageable racks on the adjacent sides thereof, a sleeve reciprocal over said overlapping bar ends, and a pin extended through one of the walls 95 of said sleeve and one of said bars.
